J. Buffington.

Meat and Fruit Cutter.

Patented Jul. 5, 1833

Inventor;
Joseph Buffington.

Joseph Buffington
Gent's Patent

The schedule referred to in this Gent's Patent and making part of the same containing a description in the words of the said Joseph Buffington himself of his improvement or combination of Machinery for cutting into small pieces flesh, fruit, vegetables or any other soft substance.

The tub or vessel in which the substance to be cut is placed must be circular, of a depth sufficient to hold the quantity to be cut at one time, the inside of its bottom forming an inclined plane from the centre to the periphery at a slight inclination. Since the centre of this tub or vessel passes a shaft around which either the tub or vessel may be made to revolve or the tub or vessel may be made stationary, the cutting knives herein after described may revolve within it.

The cutting knives may be made of metal say iron with steel edges they are in the form of a disk. There may be any number of them so as to fill the whole distance between the tub centre and the periphery of the tub, or they may be limited in which case they are placed successively nearest the periphery: whatever number there may be, they gradually diminish in size from the periphery toward the centre, corresponding to the inclination of the inside bottom of the tub.

These cutting knives are fixed upon a horizontal shaft which when the tub or vessel revolves, is turned by a wheel which may be moved by the hand or machinery, but when the tub or vessel is stationary, one end of this shaft is fastened to the first mentioned shaft in the centre of the tub & the other end of this second mentioned shaft being made to revolve around the tub as a vessel moves with it the knives.

The revolutions of the tub or vessel when it is intended to move the knives by the hand, are to be slow.

No. 716,558

upon the inside of the inclined bottom whatever number of cutting knives there may be they must be placed a short distance apart. This may vary according to the article to be cut. For cutting meat when the cutting knives are seven & a half inches in diameter I generally place the cutting knives five eighths of an inch apart. Between each knife I place a piece of metal one end of which being, fixed to a horizontal cross piece on which the knife is fixed. The other slightly touches the cutting knife on the upper side the object of which is to clean off any part of the substance intended to be cut which may adhere to the knives. What I claim as my invention & discovery, is the new & useful improvement above described of cutting knives in the form of disks gradually diminishing in size revolving within the tub or vessel in which the substance to be cut is placed & when the tub or vessel is required to move, causing it to revolve by the friction of the cutting knives of the inclined bottom of the tub.
